UNITED STATES PATENT OFFICE.

DEWEY H. BITNEY, OF AUBURN, MICHIGAN, ASSIGNOR TO UNION STEEL PRODUCTS COMPANY, OF AUBURN, MICHIGAN.

STRUCTURAL UNIT.

Application filed November 6, 1925. Serial No. 67,256.

The main objects of this invention are:

First, to provide a concrete reinforcing structural unit for beams, joist and the like which is well adapted to withstand the diagonal stresses.

Second, to provide a reinforcing structural unit which constitutes a combined chair and stirrup, is effective for the supporting of reinforcing elements and may be used in a great variety of relations.

Third, to provide an improved structural unit of the class described which is not likely to be injured or deformed in handling.

15 Objects relating to details and economies of construction and operation of my invention will definitely appear from the detailed description to follow.

The invention is clearly defined and pointed out in the claims.

A structure which is a preferred embodiment of my invention is clearly illustrated in the accompanying drawing, forming a part of this application, in which:

20 Fig. 1 is a side view of one of my improved structural units.

Fig. 2 is an end view thereof.

Fig. 3 is a cross section on line 3-3 of Fig. 1.

25 Fig. 4 is a detail view illustrating the relation of the unit in laying a concrete floor.

Fig. 5 is a fragmentary view on line 5-5 of Fig. 6 further illustrating the use of my structural unit.

30 Fig. 6 is a detail fragmentary view partially in section on line 6-6 of Fig. 5.

Fig. 7 is a fragmentary perspective view showing my improved structural unit in another structural relation.

35 In the drawing similar reference characters refer to similar parts throughout the several views.

Referring to the drawings, my improved structural unit comprises a plurality of chair members 1 disposed in spaced relation, there preferably being a chair member at each end of the unit and, in the structure illustrated, a central chair member. These chair members have bottom cross pieces 2

40 disposed in spaced relation to the lower ends of the side members or uprights 3 of the units and with the ends of the cross members projecting beyond the uprights, thereby providing vertical form spacing members 4

45 and lateral form spacing members 5.

I also provide a plurality of U-shaped stirrup members 6 which are disposed with their bottom pieces 7 in the plane of the bottom pieces 2 of the U-shaped chair members. These stirrup members are preferably 60 irregularly spaced, that is, they are closer together at one end of the unit than at the other as it is desirable where used in a flooring, for example, to have the stirrup members more closely arranged adjacent a column or other support.

The chair and stirrup elements are supported in their spaced relation by means of the bottom longitudinal rod 8 which is arranged on the underside of the bottom pieces 70 of the elements and secured thereto preferably by electric welding and the side longitudinal rods 9 which are secured on the outer sides of the uprights of the elements also preferably by electric welding.

75 The upper ends of the uprights of the chair and stirrup elements are preferably turned laterally providing the projections 10 and the longitudinal rods 9 are secured adjacent to these laterally turned ends. By 80 securing these longitudinal rods on the outside, several of the units may be nested for shipment or storage and, further, they are not likely to be knocked or broken off in the placing of the reinforcing element as the 85 bars 11 and 12. The longitudinal rods may also serve as supports for the cross pieces 13 for bent rods such as 12.

In Figs. 4, 5 and 6 I illustrate the use of my improved structural unit. The same 90 may be placed in a trough-like form 14, the spacing members properly positioning the unit. The reinforcing bars can then be positioned as desired, the whole being imbedded by the floor and beam as shown at 15— 95 see Fig. 4. In Fig. 7, I illustrate the relation where a tile, as 16, is used.

My improved structural unit is capable of wide use, is quickly placed in the forms and is effective in preventing mistakes or carelessness on the part of the workmen as is likely to occur where separate chairs and stirrups are employed.

100 The units are economically produced and are very effective for the purpose for which 105 they are designed.

Having thus described my invention, what I claim as new and desire to secure by Letters Patent, is:

110 1. A structural unit comprising a plural-

- 2
5. A structural unit comprising a plurality of U-shaped chair elements having bottom cross pieces secured in spaced relation to the lower ends of their uprights and projecting beyond the same providing vertical and lateral spacing members, a plurality of U-shaped stirrup elements disposed in spaced relation between said chair elements with their bottom cross pieces in the plane of the said cross pieces of said chair element, 10 the uprights of said chair and stirrup elements having laterally turned upper ends, a bottom longitudinal rod secured centrally to the underside of the said chair and stirrup element bottom cross pieces, and side longitudinal rods secured to the outer sides of the uprights thereof and adjacent but in spaced relation to said laterally turned ends thereof. 15
2. A structural unit comprising a plurality of U-shaped chair elements having bottom cross pieces secured in spaced relation to the lower ends of their uprights and projecting beyond the same providing vertical and lateral spacing members, a plurality of U-shaped stirrup elements disposed in 20 spaced relation between said chair elements with their bottom cross pieces in the plane of the said cross pieces of said chair element, a bottom longitudinal rod secured centrally to the underside of the said chair and stirrup element bottom cross pieces, and side longitudinal rods secured to the outer sides of the 25 uprights thereof.
3. A structural unit comprising a plurality of upright upwardly facing U-shaped chair elements having bottom cross pieces secured in spaced relation to the lower ends of their uprights and projecting beyond the same providing vertical and lateral spacing members, a plurality of upright upwardly 30 facing U-shaped stirrup elements disposed in spaced relation between said chair elements, a bottom longitudinal rod secured to said chair and stirrup element bottom cross pieces, and side longitudinal rods secured to 35 the outer sides of the uprights thereof.
4. A structural unit comprising upright upwardly facing U-shaped chair members disposed at the ends of the unit and provided with form spacing means, a plurality of upright upwardly facing U-shaped stirrup elements disposed in spaced relation to said chair elements and to each other, and longitudinal rods secured to the outer sides of said chair and stirrup elements whereby they are supported in upright relatively 40 fixed spaced relation. 45
5. A structural unit comprising upright upwardly facing U-shaped chair elements and upright upwardly facing U-shaped stirrup elements disposed in spaced relation, the chair elements being provided with form spacing members, and bottom and side longitudinal rods secured to the bottom and side members of said chair and stirrup elements whereby they are supported in relatively 50 fixed spaced relation. 55
6. A structural unit comprising upright upwardly facing U-shaped chair elements and upright upwardly facing U-shaped stirrup elements disposed in spaced relation, the chair elements being provided with form spacing members, and longitudinal rods secured to said chair and stirrup elements whereby they are supported in relatively 60 fixed spaced relation. 70
7. A structural unit comprising a plurality of upright upwardly facing U-shaped elements disposed in spaced relation, and longitudinal rods secured to said elements for supporting them in upright relatively fixed 75 spaced relation, one or more of said elements being provided with form spacing means. 80
- In witness whereof I have hereunto set my hand. 85

DEWEY H. BITNEY.
